UNITED STATES PATENT OFFICE.

FREDRICK REICHERT, OF MACON, GEORGIA.

MOSQUITO-NET FRAME.

SPECIFICATION forming part of Letters Patent No. 268,283, dated November 28, 1882.

Application filed August 31, 1882. (No model.)

To all whom it may concern:

Be it known that I, FREDRICK REICHERT, a citizen of the United States, residing at Ma-
5 con, in the county of Bibb and State of Geor-
gia, have invented certain new and useful Im-
provements in Mosquito-Net Frames and Mode
of Attachment to Bedsteads; and I do hereby
declare that the following is a full, clear, and
exact description of the same, reference being
10 had to the annexed drawings, making a part of
this specification, and to the letters and figures
of reference marked thereon.

Figure 1 of the drawings is a perspective
view of my invention applied to a bedstead;
15 Fig. 2, a detail view, showing the manner of
connecting it to a bedstead; and Fig. 3, a simi-
lar view of the socket-plates and braces.

This invention relates to frames for mosquito-
netting, the objects thereof being to produce
20 such a frame as can be readily attached to or
detached from a bedstead, and from its sim-
plicity of construction economize in space, as
I use but two uprights instead of four, as is
25 generally the case in frames of this character;
also, when not in use the upper or horizontal
portion of the frame, from which depends the
netting, may be folded back against the up-
right in a vertical position, and the whole
30 device lowered below the head-board of a bed-
stead, out of sight, and as readily raised and
placed in position, when so desired, there be-
ing no loose pieces to become scattered or lost.
These objects I attain by the construction sub-
35 stantially as shown in the accompanying draw-
ings, and hereinafter described, and pointed out
in the claim.

In the drawings, A represents the two up-
right pieces, either of wood or metal, which are
secured to the head board or posts of a bed-
40 stead by means of clamps B, attached thereto,
said clamps being provided with thumb-screws
a, by which the uprights may be held at any de-
sired height. At the top of each of these up-
right A are secured angle-plates b, between
45 which are placed the ends of the horizontal or
top frame, C, and pivotally connected thereto
by means of a rod, D, passing through the said
angle-plates and ends of the horizontal or
top frame from one side to the other. At a
50 suitable distance from the rear ends of the
horizontal or top frame, C, are pivotally secured
braces E, extending in a diagonal direction to-

ward the uprights A, each of these said braces
being provided with a foot, c, which connect
with socket-plates d, secured upon the uprights 55
A. These feet c of the braces are provided
with countersunk depressions e, to receive the
pointed end of a set-screw, F, to regulate and
secure the frame C at the proper elevation.

When the device is not desired for use the 60
set-screws F are unscrewed sufficiently to allow
of the feet c being lifted out free of the socket-
plates d, when the frame C, pivotally con-
nected between the angles-plates b upon the
uprights A, is thrown up out of the way in a 65
line with said uprights or turned down en-
tirely against the same, and, if so desired, the
whole device lowered below the head-board of
the bedstead, out of sight, by loosening the
70 thumb-screws a in the clamps B.

It will be seen from the foregoing descrip-
tion that I have constructed a frame for mos-
quito-netting that may be readily attached to
or detached from any bedstead, and which,
from its simplicity of construction, may be 75
quickly adjusted for use or placed entirely
out of sight, when not needed, without remov-
ing it from the said bedstead; also, the device
may be easily taken down and packed away
80 in a comparatively small space, and, there be-
ing no parts to become scattered or lost, it is
always ready to be set up when desired for
use.

Having now described my invention, what I
claim, and desire to secure by Letters Patent, 85
is—

The combination of the uprights A, provided
with angle-plates b and socket-plates d, se-
cured to a bedstead by clamp B, and held at
any desired height by the thumb-screws a, with 90
the horizontal or top frame, C, rod D, and piv-
otal braces E, said braces having feet c, pro-
vided with countersunk depressions e to re-
ceive the ends of set-screws F in the socket-
plates d, all arranged to operate substantially 95
as and for the purpose set forth.

In testimony that I claim the above I have
hereunto subscribed my name in the presence
of two witnesses.

FREDRICK REICHERT.
